UNITED STATES PATENT OFFICE.

WILLIS A. BROWER, OF ADRIAN, MICHIGAN, ASSIGNOR TO MICHIGAN MUTUAL LIABILITY COMPANY, OF DETROIT, MICHIGAN, A CORPORATION OF MICHIGAN.

SAFETY ATTACHMENT FOR PUNCH PRESSES.

1,418,525.

Specification of Letters Patent. Patented June 6, 1922.

Application filed August 27, 1921. Serial No. 495,952.

To all whom it may concern:

Be it known that I, WILLIS A. BROWER, a citizen of the United States of America, residing at Adrian, in the county of Lenawee 5 and State of Michigan, have invented certain new and useful Improvements in Safety Attachments for Punch Presses, of which the following is a specification, reference being had therein to the accompanying drawings.

This invention relates to safety attachment for punch presses, and it is the object of the invention to provide a punch press with a guard member which is required to engage the table of the press prior to operation of the punch so that the operator is not permitted to place his hand in the path of the punch during the down-stroke thereof. The object of the invention is furthermore to so arrange and actuate the guard that it will engage the operator's hand if the latter is in the path of the punch, being prevented by such engagement from being lowered to its protective position and consequently preventing release of the punch actuating mechanism.

A preferred embodiment of the invention is hereinafter described and is illustrated in the accompanying drawings, wherein:

30 Figure 1 is a view in side elevation of a punch press equipped with the improved protective attachment, the punch being shown in its raised position, and the guard member of the attachment being likewise raised;

35 Figure 2 is a similar view of a press showing the guard member lowered preliminary to a stroke of the punch;

40 Figure 3 is a similar view showing the position of the press during the initial portion of the up-stroke of the punch;

Figure 4 is an enlarged view of a portion of the mechanism as shown in Figure 1;

45 Figure 5 is a similar view of the same mechanism as shown in Figure 2;

Figure 6 is a vertical sectional view taken on line 6—6 of Figure 5;

Figure 7 is a detail perspective view of the guard member.

50 In these views, the reference character 1 designates the table of a punch press, and 2 the rotative tripping wheel controlling the punch 3, said wheel being operated by any suitable clutch mechanism (not shown).

The wheel has a peripheral cam portion 2^a, 55 one end of which forms a radial shoulder 2^b, engageable by a dog 2^c to normally maintain the raised position of the punch. 4 is a guard member carried by the forward end of an arm 5, the rear end of which arm is 60 secured to a rocker disk 6 pivoted at 7 upon the standard 8 of the press. The mechanism of the press (not shown in detail) is controlled by a foot lever 9 pivoted upon the base portion of the standard 8. The arm 5 65 which carries the guard member is intermediately pivotally engaged at 10 by the forward end of a swinging link bar 10', the rear end of which is connected to the lower extremity of a trip release bar 12 by a pivot 70 pin 13. An operating connection is established between the foot lever 9 and the members 10' and 12 by a pull-rod 14 engaging said pivot pin. The trip release bar 12 is pivoted at its upper end to said dog 2^c which 75 controls the operation of the punch through engagement with the trip wheel 2. 16 is a disk parallel and adjacent to the disk 6 and fixedly secured to the standard 8 of the press, said disk being formed with a 80 circumferential slot 17 and also with a substantially radial slot 18, the latter being extended inwardly from the forward end of the slot 17 and being so positioned as to substantially register with the pivot 85 pin 13 when the guard 4 is engaged with the table 1. Said pivot pin engages in a substantially radial slot 19 in the disk 6, and also in the connected slots 17 and 18 of the disk 16, being maintained, in the normal 90 position of the parts (shown in Figs. 1 and 4), in the rear end of said slot 17. When the foot lever 9 is depressed, the disk 6 is thereby rocked, through the link 14, swinging the arm 5 downwardly and lowering the 95 guard 4, and also registering the radial slot in said disk and pin 13 engaged in said slot with the radial slot 18 in the disk 16, as the guard member 4 is engaged with the table 1. When the radial slots 18 and 19 are in the 100 described registering relation further downward actuation of the foot lever 9 moves the pivot pin 13 radially inward in said slots 18 and 19, shifting the release bar 12 downwardly, disengaging the dog 2^c from the 105 shoulder 2^b of the trip wheel 2, and initiating the down-stroke of the punch. During said stroke, the guard member 4 is locked in en-

gagement with the table 1 by engagement of the pin 13 in the slot 18, such engagement preventing the rotation of the disk 6, requisite to raise the arm 5. Said pin cannot escape from said slot until the tripping wheel 2 has rotated sufficiently to carry the cam portion 2^a clear of the dog 2^c, allowing the latter to swing up to its normal position, in which it may again engage the shoulder 5 2^b, while the rod 12 is at the same time raised to register the pin 13 with the circumferential slot 17. The coil spring 24, attached to the bar 12 serves to effect a return of said bar and also of the inter-connected 10 parts 9, 10', 13 and 14 to their normal position. A coiled spring 25 acts upon the arm 5 to raise said arm and the guard 4 after the normal position of the parts 9, 10', 13 and 14 has been established. It is to be 15 noted that the rod 12 is locked in raised position until the guard has again been lowered.

What I claim as my invention is:

1. In a safety attachment for machines, the combination with the table of a machine 25 and a tool movable to and from said table, of a trip mechanism controlling said movement of the tool, a guard member for said tool, a pivotal arm carrying said guard member having a lateral extension from its pivotal end slotted substantially in the direction of the pivot, a trip release bar actuatable toward the pivotal end of said arm to effect release of said trip mechanism, a pin carried by said bar and engaging in said slot, a stationary abutment engaging said pin between the same and the pivot of said arm to normally lock said trip release bar against releasing movement, and means engaging said pin for rocking said arm to lower the guard 30 to its protective position and thereby shift said pin clear of said abutment, and for subsequently shifting said pin and the trip release bar toward the pivot of the arm to release the trip mechanism.

45 2. In a safety attachment for machines, the combination with the table of a machine and a tool movable to and from said table, of a trip mechanism controlling said movement of the tool, a guard member for the 50 tool, an arm carrying said guard member having a lateral extension from its pivotal end slotted substantially in the direction of the pivot, a trip release bar actuatable toward the pivotal end of the arm to effect release of 55 the trip mechanism, a pin carried by said bar and engaging in said slot, a stationary member formed with a slot describing an arc about the pivot of said arm and having an extension at one end substantially toward 60 said pivot, and means engaging said pin for initially rocking said arm to lower the guard to its protective position and through said initial rocking of the arm registering the slot thereof with the similar slot of said stationary member, and for subsequently shift-

ing said pin in the registered slots toward the pivot of said arm and thereby actuating the trip release bar to release position.

3. In a safety attachment for machines, the combination with the table of a machine 70 and a tool movable to and from said table, of a trip mechanism controlling said movement of the tool, a guard member for the tool, an arm carrying said guard member having a lateral extension from its pivotal end slotted substantially in the direction of the pivot, a trip release bar actuatable toward the pivotal end of the arm to effect release of the trip mechanism, a pin carried by said bar and engaging in said slot, a link extending from 75 said pin to an intermediate portion of said arm, a stationary abutment engaging between said pin and the pivotal end of the arm in the normal position of the parts, restraining said trip release bar against releasing movement, and means engaging said pin for rocking said arm to lower the guard to its protective position, while shifting said pin clear of said abutment, and subsequently shifting said pin and the trip release bar 80 toward the pivot of the arm to actuate the release bar to release position.

4. In a safety attachment for machines, the combination with the table of a machine and a tool movable to and from said table, of a trip mechanism controlling said movement of the tool, a guard member for the tool, an arm carrying said guard member having a lateral extension from its pivotal end slotted substantially in the direction of the pivot, a trip release bar actuatable toward the pivotal end of said arm to effect release of the trip mechanism, a link through which said release bar and said arm are actuated, a pin 90 pivotally connecting said link to the release bar, a stationary abutment engaging in the normal position of the parts between said pin and the pivot of the arm and normally restraining the release bar against releasing movement, and means for actuating said link to rock said arm to initially lower the guard member and shift said pin clear of said abutment, and to subsequently actuate said pin and the release bar toward the pivot 95 of the arm to establish release position of the release bar.

5. In a safety attachment for machines, the combination with the table of a machine and a tool, movable toward and away from said table, of a trip mechanism controlling the movement of said tool, a trip release bar movable longitudinally to effect release of said trip mechanism, a guard for said tool movable adjacent to said table, a rotatable member carrying said guard and controlling the longitudinal releasing movement of said trip release bar, means for normally locking said trip release bar from longitudinal releasing movement, and means engaging said trip release bar for rotating said guard car- 100 105 110 115 120 125 130

rying member to move said guard adjacent to said table and to release said trip release bar from said locking means and for subsequently moving said trip release bar longitudinally to release said trip mechanism.

6. In a safety attachment for machines, the combination with the table of a machine and a tool movable to and from said table, of a guard member for said tool, a tripping wheel and coacting dog controlling operation of said tool, said wheel having a cam portion terminating in a shoulder normally engaged by said dog to restrain the tool from operation, and a common means for shifting said guard to protective position adjacent said table and for subsequently withdrawing said dog from said shoulder of the tripping wheel, the cam portion of said wheel being engaged by said dog during the succeeding stroke of the tool to lock the guard in protective position.

7. In a safety attachment for machines, the combination with the table of a machine, and a tool movable to and from said table, of a wheel having a peripheral cam portion provided at one end with a shoulder, a dog engaging said shoulder, a guard member for

said tool, and means for lowering said guard member and subsequently actuating said dog to permit said tool to move downwardly, 30 said means cooperating with said dog for locking said guard member in a lowered position during the entire movement of said tool.

8. In a safety attachment for machines, 35 the combination with the table of a machine and a tool, movable toward and away from said table, of a trip mechanism controlling the movement of said tool, a trip release bar for effecting release of said trip mechanism, 40 a guard for said tool movable adjacent to said table, a member carrying said guard and controlling the releasing movement of said trip release bar, means for normally locking said trip release bar from releasing 45 movement, and means engaging said trip release bar for actuating said guard carrying member to move said guard adjacent to said table and to release said trip release bar from said locking means and for subsequently moving said trip release bar to release said trip mechanism.

In testimony whereof I affix my signature.

WILLIS A. BROWER.
